PENNSYLVANIA

TERMINAL CONNECTER

Application filed March 17, 1928. Serial No. 262,355.

This invention relates to terminal connectors and more particularly to terminal connectors for connecting the lead wires of storage batteries to the terminal posts thereof.

An important object of the invention is to provide a device of this character which may be very rapidly and easily removed from the terminal post of the battery.

A further object of the invention is to provide in a device of this character an attachment for the terminal post and a lead connector which has engagement with the terminal post attachment in such fashion that a proper contact therebetween is assured and, at the same time, a structure produced, the sections of which are readily separable.

These and other objects we attain by the construction shown in the accompanying drawings, wherein for the purpose of illustration is shown a preferred embodiment of our invention and wherein:—

Figure 1 is a plan view of a connector constructed in accordance with our invention;

Figure 2 is a side elevation thereof;

Figure 3 is a vertical sectional view therethrough;

Figure 4 is a plan view showing the connector in the process of engagement or separation of the sections thereof;

Figure 5 is a side elevation of the male section.

Referring now more particularly to the drawing, the terminal connector comprises a post engaging section 10 and a lead engaging section 11. The post engaging section 10 is in the form of a trunco-conic sleeve 12, the lower end of which is split, as at 13, at a plurality of points so as to permit expansion of the lower end of the sleeve. The upper end of the sleeve is preferably provided with a wrench square 14 and the sleeve has directed therethrough intermediate its ends a pin 16, the ends of which project beyond the outer face of the sleeve.

The lead engaging section has a socket 17

for the reception of the lead wire 18 and further embodies an open-topped trunco-conic sleeve 19, the upper edge wall of which is formed with cam faces 20 terminating adjacent abrupt shoulders 21. The interior of the sleeve in alignment with these shoulders is longitudinally grooved, as indicated at 22. The grooves 22 permit the ends of the pin 16 which are spaced apart a distance greater than the diameter of the upper end of the sleeve 19 to be positioned over the upper end wall for engagement with the cam faces 20 thereof.

In operation, the male section is forced over the terminal post 23 of the battery and the sleeve 19 placed in position thereover. With the pins 16 in engagement with the cam surfaces 20, it will be obvious that upon rotation of the lead wire engaging element of the connector, the sleeve 19 will be forced downwardly, forcing the wings of the sleeve 12 inwardly for firm engagement with the terminal post, so that a good mechanical as well as electrical connection between the terminal post and the sections of the connector is provided.

The cam faces 20 are separated by flat sections 22 with which the ends of the pin 16 may be engaged, so that the connection will not be displaced by vibration during use.

Since the construction, hereinbefore set forth is capable of a certain range of change and modification without materially departing from the spirit of the invention, we do not limit ourselves to such specific structure except as hereinafter claimed.

We claim:—

In a terminal connector for connecting the leads and terminal posts of storage batteries and the like, a hollow post engaging section comprising a split conical sleeve and the lead engaging section having a solid conical sleeve, said sleeves being engageable with one another, the post engaging sleeve having a projecting pin adjacent its upper end, the up-

per end of the sleeve of the lead engaging element having a cam surface for coaction with said pin to cause relative longitudinal movement of the sleeves upon relative rotation thereof, the sleeve of the lead engaging section having a groove for the passage of said pin the upper end of the split conical sleeve being closed and provided with a polygonal head for engagement with the wrench.

10 In testimony whereof we hereunto affix our signatures.

DANIEL KNOEPFLE.
SAMUEL R. FELDMAN.
